APPARATUS FOR THE CONCENTRATION OF
SULPHURIC ACID

Harry Pauling, Berlin, Germany

Application November 7, 1938, Serial No. 239,316
In Germany October 17, 1936

5 Claims. (Cl. 23—274)

For the concentration of sulphuric acid there are employed in general large boilers with attached dephlegmators, in which continuously about 20 tons of concentrated sulphuric acid are kept boiling. The space occupied by the boilers, the diameter of which amounts to about 2.5 meters, is relatively large in comparison to their efficiency. A disadvantage also lies in the fact that in the case of burning through of a boiler 5 large quantities of boiling hot highly concentrated sulphuric acid leak into the combustion chamber and thus the workmen and the operation of the factory are greatly endangered.

According to the present invention the greatest security of operation and a considerably higher efficiency with considerably less occupation of space are attained in such a manner that with the same output compared with the customary boilers at any time only a little sulphuric acid takes part in the concentration, which is effected in a single tube which is constructed at its lower part as a film evaporator and in its upper part as a rectification device. The efficiency of such tubes in comparison to the boilers is much 20 higher on account of the fact that the heating surfaces are better utilised. The strength of the wall of the tube is in each case less than that of a boiler and in addition the rate of streaming of the sulphuric acid is greater in a tube than in a 25 boiler. The better utilisation of the heating surfaces also entails a considerable economy of material.

The lower portion of the tube, which is constructed as a film evaporator, lies completely 30 within a heated chamber while the rectification portion projects out over the heated chamber in such a manner that at that part a rectification of the sulphuric acid-water vapours rising from the film evaporator is rendered possible with the 35 sulphuric acid to be concentrated, which is delivered at the top in the rectification portion. The rectification portion is obviously intended to be well insulated; it can if desired also be subjected to a gentle heating by the waste gases of the 40 actual heating zone. In the rectification portion bubble caps or similarly operating devices are arranged.

In order to effect the result that the sulphuric acid streaming out of the rectification portion 45 trickles down in a thin layer on the wall of that part of the tube serving as evaporator, this part, as has already been proposed for sprinkling evaporators, is completely filled with material in small pieces, for it is a known phenomenon that 50 in a so-called filling column the liquid, even when

it is delivered at the top in the middle of the tube cross section, after a relatively short streaming distance only streams down the wall in a thin layer. The same result is obviously also attained by the known arrangement of a plate 5 at the upper end of the evaporator tube which conducts the sulphuric acid coming from the rectification portion to the wall.

Since in the concentration of sulphuric acid sludge may easily be deposited it is suitable in 10 the lower portion of the tube to arrange coaxially a narrower tube which consists of the same material as the tube lying in the fire chamber, or, since a good heat conductivity of this tube is not necessary, it may be constructed of cheaper 15 resistant ceramic material. In the walls of this tube are provided slits or borings which from the exterior inwards are inclined upwards and serve for passing the vapours into the interior of the narrower tube. This interior remains free 20 while the annular chamber formed by the two tubes is filled with material in small pieces.

When the sulphuric acid to be concentrated is supplied to this intermediate space not continuously but for example for a few seconds every 25 minute, there is produced a so-called liquid plunger which sinks within the filling with a definite velocity in such a manner that it completely fills the intermediate space between the individual small filling elements. Thus a thorough rinsing 30 of the material in small pieces takes place without the quantity of liquid being increased calculated over a long period.

The individual tubes are at their lower ends, which suitably lie outside the fire chamber, provided with a closure which collects the concentrated sulphuric acid flowing downwards and from which it is supplied for further use, whether to a collecting tube or to a separate or common 35 cooler.

The apparatus according to the invention is 40 illustrated in the accompanying drawing. In the drawing Figures 1 and 2 are illustrations of the apparatus in section elevation, Figures 3 and 4 in cross section, and Fig. 5 shows a modification 45 in which a plate is used at the upper end of the evaporator tube. Referring to Fig. 1, the lower portion of the vertically arranged tube, which is intended to serve as a film evaporator, is marked *a*, the upper part intended for rectification is indicated by *b*. The rectification portion is provided with bubble caps located in a series of partitions *c* on which takes place the rectification between the sulphuric acid-water vapours streaming up from below and the sulphuric acid 50 55

supplied through the pipe *d*. Coaxially arranged in the tube portion *a* is a narrower tube *e* with inclined slits *f* passing from bottom to top towards the interior, through which the sulphuric acid-water vapours pass into the interior of the tube and stream upwards with slight excess pressure. The intermediate space between the tubes *a* and *e* is provided with a filling *g* in small pieces. The concentrated sulphuric acid passes out at 10 the lower end of the tube *a* through the outlet *h*, while on the other hand water vapours escape at the upper end of the tube portion *b* through the outlet *i*. The tube portion *a* is located in the heating chamber *k* in which the fire gases enter 15 through the opening *l* and pass out through the opening *m*.

It has been shown that a single tube of greater length can be composed of several small tubes without the packings which are subjected to the 20 attack both of the fire gases and also of the sulphuric acid, being injured, which was to be feared. This is due to the fact that at the packings no hydrostatic pressure prevails, since the tubes are not completely filled with sulphuric 25 acid but this flows down on the interior surfaces of the tube walls.

As previously mentioned, a plate can be used at the upper end of the evaporator tube *a* for conducting the sulphuric acid to the inner wall 30 thereof. This construction is illustrated in Fig. 5, wherein the reference letter *p* indicates an annular plate secured to the inner tube *c* and sloping downward toward the evaporator tube *a*, from 35 which it is separated by a narrow annular slot. The acid delivered to the space above the plate flows through the slot and down the wall of the evaporator tube.

According to Figures 2, 3 and 4, which are on a smaller scale, a large number of tubes for example with a diameter of 300 mm. is arranged 40 about a generator which serves for the gasification of the combustible material necessary for the heating operation. On account of this arrangement not only is a very large heating surface attained in relatively small space, but also 45 loss of heat by the generator by radiation into the external surroundings is avoided.

In the arrangement of for example 32 tubes each of four square metres heating surface in 50 two annular series about a generator according to Figure 3, 128 square metres of heating surface can be brought into a unit element of 4 x 4 m. area at the base and 5 m. actual height with 2 m. height of the base.

If the tubes lie in the form of a horseshoe 55 about the generator according to Figure 4, the charging of the generator and the removal of the cinders is possible from the back instead of from the top and bottom.

I claim:

60 1. In an apparatus for the concentration of

sulphuric acid, a vertical tube comprising a lower evaporating section and an upper rectifying section, means for heating the lower section, means for introducing dilute acid at the top of the upper section, means for causing the acid after 5 leaving the upper section to flow down the interior wall of the lower section in a thin stream, a vapor passage extending centrally upward through said lower section to the rectifying section, an outlet for water vapor at the top of the 10 upper section, and means for withdrawing concentrated acid from the bottom of the lower section.

2. In an apparatus for the concentration of sulphuric acid, a vertical tube comprising a lower 15 evaporating section and an upper rectifying section, means for heating the lower section, means for introducing dilute acid at the top of the rectifying section, an inner tube concentric with and spaced away from the lower section of the 20 first tube, the interior of the second tube communicating with the rectifying means in the first tube, means for delivering the acid to the space between said tubes when it leaves the said upper section, a filling between said tubes for causing 25 the acid to flow down the tube surfaces in thin streams, openings in the wall of the second tube for the passage of vapors, an outlet for water vapor at the top of the said upper section, and means for withdrawing concentrated acid from 30 the bottom of the said lower section.

3. In an apparatus for concentrating sulphuric acid, a vertical tube, a series of partitions in the upper section of said tube equipped with bubble 35 caps and overflow pipes, means for introducing dilute acid at the top of the tube, a second tube concentric with and spaced away from the lower section of the first tube, the interior of the second tube communicating with the bubble cap in the lowermost partition and the overflow pipe in said 40 partition emptying into the space between said tubes, a filling in said space to cause the acid to flow down the tube surfaces in thin streams, means for applying heat to the lower section of the first tube, openings in the wall of the second 45 tube for the passage of vapors, a vapor outlet at the top of the first tube, and means for withdrawing concentrated acid from the bottom of the first tube.

4. Apparatus for concentrating sulphuric acid 50 comprising a plurality of vertical tubes as claimed in claim 1, and a common heating means around which the said tubes are arranged in a circular formation.

5. Apparatus for concentrating sulphuric acid 55 comprising a plurality of vertical tubes as claimed in claim 1, and a common heating means around which said tubes are arranged in a horseshoe-shaped formation.

HARRY PAULING.
